US0D1106631S

(12) **United States Design Patent** (10) **Patent No.:** **US D1,106,631 S**
(45) **Date of Patent:** **** Dec. 16, 2025**

(54) **SHOPPING CART**

(71) Applicant: **Maplebear Inc.**, San Francisco, CA (US)

(72) Inventors: **YanYing Tai**, Shanghai (CN); **Xin Wang**, Shanghai (CN); **Yilin Huang**, Shanghai (CN); **Lin Gao**, Miami, FL (US); **Weiting Chen**, Shanghai (CN); **Zhouliang Cao**, Shanghai (CN); **Liang Yang**, Shanghai (CN); **Linhua Luo**, Shanghai (CN)

(73) Assignee: **Maplebear Inc.**, San Francisco, CA (US)

(**) Term: **15 Years**

(21) Appl. No.: **29/987,863**

(22) Filed: **Jan. 27, 2025**

CLAIM

The ornamental design for a shopping cart, as shown and described.

DESCRIPTION

FIG. 1 is a first perspective view of a shopping cart.

FIG. 2 is a second perspective view of the shopping cart.

FIG. 3 is a front view of the shopping cart.

FIG. 4 is a rear view of the shopping cart.

FIG. 5 is a first side view of the shopping cart.

FIG. 6 is a second side view of the shopping cart.

FIG. 7 is a top-down view of the shopping cart; and,

FIG. 8 is a bottom-up view of the shopping cart.

The broken lines shown in the drawings depict portions of the shopping cart that form no part of the claimed design.

1 Claim, 8 Drawing Sheets
